In Germany August 7, 1937

8 Claims. (Cl. 250—27.5)

The present invention relates to the construction of gas- or vapor-filled discharge vessels for high operating voltages in which a discharge passes between an electron emitting source and one or more anodes and which may be used to control or convert high-voltage currents. To this end it has already been proposed to effect a uniform distribution of the voltage along the discharge path by means of intermediate electrodes lying between the electron emitting source and the anode. However, this means is not sufficient to ensure a proper operation at high operating voltages. According to the invention the intermediate electrodes are so designed that the lines of force running between the electrodes following one another are substantially inclined to the discharge path and deviate the ions or electrons present in the discharge space towards conducting parts. It is particularly advantageous to design the electrode in such a manner that a plurality of channels result whose dimensions are relatively small in the direction perpendicular to the discharge path. The ions or electrons which are deviated in either direction impinge upon a metallic part after having travelled a relatively short distance. It is advisable to make the length of the single chambers of the part, for instance, in the form of a honeycomb equal to or greater than the width thereof.

In Figs. 1 and 2 of the accompanying drawings is shown a pair of such electrode systems. They consist of a honeycomb-like part 1 which is composed of a cylindric tube 2 of a comparatively large diameter (Fig. 2) and of various smaller tubes 3 surrounded by the tube 2. Integral with the honeycomb-like part 1 is a cylindrical part 4 of greater diameter which encloses the honeycomb-like part of the next following electrode system. The central zone of the honeycomb-like part extends into the preceding electrode. In this manner a field distribution is attained which is similar to that which would result between two adjacent spherical shells. By finer subdivisions of the honeycomb-like part and suitable grading of the individual zones a field distribution may be brought about which is very similar to the field distribution between the two spherical shells. The field distribution is indicated by the dotted lines lying between the electrodes. By the lines of force running between the adjacent electrodes and which are inclined to the discharge path, particles are deviated—regardless of whether they are positively or nega-

tively charged and no matter whether they travel in a direction towards the anode or towards the cathode of the discharge vessel—and impinge upon metallic surfaces of the intermediate electrodes. In this manner they are prevented from reaching the discharge path and are rendered innocuous. Instead of the honeycomb-like part also various concentrical cylinders may be employed.

In the case of the rotation symmetrical intermediate electrodes as shown this effect is not utilized to its full extent as regards the ions and electrons travelling along the axis of rotation. To render innocuous also these ions and electrons they may be directed into a hollow space of the anode which is substantially free of lines of force so that the electrons released by the particles impinging upon the electrodes cannot substantially cause an ionization of the discharge path.

Another method consists in the fact that the centrally travelling ions or electrons are directed towards intercepting surfaces of the intermediate electrodes. To this end, for instance, the central tube of the tubes 3 (Fig. 2) may be closed by a metal disk. It is preferable to arrange this metal disk in the middle of the tube as shown in Fig. 1. The intercepting surface in this figure is denoted by the numeral 5. By this arrangement the intercepting surface is arranged in a space substantially free of lines of force so that also there the electrons released by the impinging ions or electrons do not cause any disturbances.

To prevent the centrally flying particles from impinging upon the emissive parts of the cathode it is preferable to arrange in front of the cathode a hollow body whose opening is directed towards the cathode and into which body pass the ions or electrons flying towards the cathode. A cathode thus protected is shown in Fig. 3. 20 is an indirectly heated hollow cathode surrounded by the metallic sleeve 21. In this sleeve is suspended the capsule 22, for instance, by means of a perforated sheet. In the cylinder 21 may also be arranged a honeycomb-like part and the end of the central chamber facing the cathode may be closed. 23 is an intermediate cathode designed as shown in Fig. 1.

Fig. 4 shows a discharge vessel according to the invention. 6, 7, 8, 9, 10 and 11 are intermediate electrodes which are designed in the manner as shown in Figs. 1 and 2. 12 is the anode which is provided inside with a bulb-shaped recess 13, into which pass the centrally flying ions or electrons. By suitably designing the anode 12 the lines of force between this anode and the adjacent intermediate electrode 11 may be caused to run in a

similar manner as between the intermediate electrodes so that the same conditions are present also in the last step of the tube. 14 denotes the cathode. In this case it is assumed that a hollow cathode is employed in which alkaline earth metal oxides are used as electron emitting substances. Instead of a hot cathode also an auxiliary discharge, particularly an auxiliary arc, in Hg-vapor may be employed. In this case it is advisable to cause in the neighborhood of the cathode a condensation of the metal vapor developed, suitable cooling arrangements being provided for this purpose. In front of the cathode is arranged the control electrode 15 which is designed in a similar manner as the lower part of the intermediate electrodes (Fig. 2). Below the control electrode are arranged two metal cylinders, one of which 16 encloses the cathode, the leads and under circumstances the squash. The upper part of the control electrode is secured to a cylindrical extension of a large diameter which encloses the honeycomb-like part of the intermediate electrode 6. Also the lines of force between the intermediate electrode 6 and the control electrode 15 inclusive of the cylindrical part 17 run substantially in the same manner as the lines of force between the intermediate electrodes. The discharge vessel may be filled up with mercury vapor, inert gases or with a mixture of inert gases and metal vapors. 30 As will be seen from Fig. 4 the edges of the single electrodes are rounded off in order to avoid too high field densities at some points of the electrode.

In the embodiment shown in Fig. 4 the honeycomb-like parts of the intermediate electrode are directed towards the cathode. However, also an inverted construction may be employed, since the ions or electrons flying into the discharge space are deviated towards metallic surfaces irrespective of the polarity or the direction of travel thereof.

The above considerations as to the behavior of load vehicles in the discharge space are only applicable if the discharge has not yet been ignited. 45 As soon as the discharge ignites, i. e., for instance, in the direction of flow in the case of a rectifier operation or if the discharge has been initiated with the aid of the control grid in the case of a controlled discharge vessel the discharge 50 is not appreciably influenced by the intermediate electrodes so that the discharge may burn without hindrance.

In the device according to Fig. 4 it has been assumed that the central portion of the intermediate electrodes 6 to 11 is provided with intercepting surfaces according to Fig. 1 (as indicated by 5). As above mentioned it is sufficient to provide the inside of the anode with a recess. This applies particularly to cases where 60 the impinging point of the stream of ions lies as deep as possible in the anode, so that the greatest part of the neutral and charged particles issuing from the impinging point impinge upon the walls of the recess and do not therefore pass into the discharge space proper. The material at the impinging point of the stream of ions is preferably of such a nature that it disintegrates to the smallest possible extent and emits a small amount of secondary electrons. 65 Such a material may also be inserted in an electrode consisting of another material in a similar manner as is performed in the case of anti-cathodes of X-ray tubes provided with tungsten sheets.

70 The electric fields prevailing between the in-

termediate electrodes are naturally only effective if a suitable voltage is applied to the electrodes during the periods for which no discharge is desired. In view of the disruptive strength of the discharge vessel voltages lying between the anode and cathode potential are supplied according to the invention to the intermediate electrodes, for instance, with the aid of a capacitive potentiometer. When dimensioning this potentiometer care should be taken to bring about an approximately uniform voltage distribution owing to the different distribution of the capacity (capacities to earth and the capacities of the electrodes with respect to one another). Such a capacitive potentiometer is shown schematically in Fig. 5. For the sake of simplicity also the intermediate electrodes are schematically shown. 27 denotes the hot cathode, 26 the heating battery and 24 the current consuming device. The energy is supplied by an alternating-current source 28 and is transmitted by a transformer 25 to the circuit including the current consuming device. In general it will be necessary to cause a decrease of the value of the capacities of the potentiometer from the anode 25 in the direction towards the cathode, since the self-capacity of the electrodes of the discharge vessel varies in the opposite direction. It is also possible to employ the self-capacities of the electrodes for dividing the voltage. However, this method can only be employed in particular cases and only if the construction of the tube permits a sufficiently accurate adjustment of the capacity values between the electrodes.

It has been found advantageous to choose the differences of potential between the anode and the next following intermediate electrode and between the grid and the adjacent intermediate electrode somewhat smaller than the differences of potential between the other electrodes. To this end care must be taken to see that the capacities anode-intermediate electrode and grid-intermediate electrode respectively are greater than the capacities between the intermediate electrodes. The reason for the increased disruptive strength of an arrangement thus dimensioned lies apparently in the fact that the voltage surges occurring during the switching operations make themselves particularly felt at the ends of the discharge vessel.

In the tube above-described it has been assumed that an electron emitting source always ready for operation is present in the form of a hot cathode or of an auxiliary discharge. The increased disruptive strength of the tube may, however, be utilized according to the invention if the auxiliary discharge is only initiated for igniting the vessel. (Ignitron.)

As above pointed out the projecting parts of the intermediate electrodes may be either directed towards the cathode or towards the anode, since the ions or electrons are deviated under all circumstances towards metallic parts. However, the results in both cases are not exactly the same. Undesirable discharges are avoided with greater certainty if the projecting parts of the intermediate electrodes are directed towards the electrode which is positive in the moment under consideration. In the embodiment shown in Fig. 2 an undesirable discharge is therefore avoided with greater certainty during the inverse phase. This depends upon the fact that the electrons released by the positive ions at the intermediate electrodes are directed back to the intermediate electrodes, whereas in case the current flowing

in the opposite direction they impinge upon the next intermediate electrode and may ionize on their way to the latter and release further electrons at the electrode itself. Therefore, the intermediate electrodes will be arranged in such a direction as to attain the greatest protection against undesirable discharges for the conditions of operation of particularly long duration. In the case of a rectifier, particularly of the multi-phase type, connected to a counter-voltage this applies to the inverse phase. The intermediate electrodes will therefore be arranged in the direction shown in Fig. 2. Under circumstances the same conditions may be obtained for both directions of current by the fact that intermediate electrodes are arranged in an alternative sense. For the same purpose also symmetric intermediate electrodes may also be employed which may be obtained if corresponding sides of two of the intermediate electrodes shown in Fig. 1 are connected.

The arrangement of the intermediate electrodes according to the invention entails the lateral bringing out of the leads for the individual electrodes, since the tubes have a rather great length. The dissipation of heat through the current supply leads is relatively great so that the degassing of the electrodes is hardly possible with the aid of high frequency and it may easily happen that the seals get damaged. The construction shown in Figs. 6 and 7 is therefore employed to advantage, which differs from that shown in Fig. 4 in that the electrodes are secured in a particular manner. The intermediate electrodes and under circumstances also the control grids are secured in a supporting tube of quartz or a ceramic material.

This supporting tube is placed after mounting the electrodes in the discharge vessel proper and is there held in the desired position. In this case there remains a small distance between the discharge vessel and the supporting tube and the intermediate electrodes respectively, so that when de-gassing the electrodes there is no fear of damaging the wall of the vessel. Furthermore, by designing the holding members for the intermediate electrodes in a suitable manner only small amounts of heat are transferred to the supporting tube.

Such an embodiment of the invention is shown in Fig. 6. 31 denotes the wall of the discharge vessel, 32 is a cathode. It is assumed that in this case an indirectly heated hollow cathode is employed. Instead of such a cathode also an auxiliary discharge, for instance, an auxiliary arc in mercury vapor may be employed which is arranged in this case preferably laterally of the anode tubes. The supporting tube consisting, for instance, of quartz is denoted by the numeral 62. The anode 33, the intermediate electrodes 34, 35 and under circumstances other intermediate electrodes of the same or similar construction (not shown) are secured within this tube. Furthermore, the two grids 36 and 37 are arranged in the supporting tube. These grids may serve a variety of purposes, for instance, for control purposes or to check ions or electrons. The lower end of the grid 37 is provided with a cylindrical extension surrounding the cathode and ending in a holding device for the supporting tube.

The intermediate electrodes and the grids are preferably secured in such a manner that these electrodes are surrounded by a U-shaped ring 38 as shown in Fig. 7. This ring has a somewhat smaller diameter than the supporting tube 62 so

as to prevent an immediate transfer of heat between these parts. The screw 39 lying in bores of the supporting tube is screwed into this ring. One of these screws may be provided with a current supply wire for the intermediate electrodes. It is preferable to determine the position of the electrodes with respect to the supporting tube by resilient fingers in such a manner that the heat carried off by the electrodes will not deteriorate the supporting tube.

The intermediate electrodes consist of a plurality of tube sections of different diameter lying within one another and which are displaced in axial direction with respect to each other for the purpose of forming a field of a suitable configuration. The central cylinders are besides closed by intermediate walls 40 which serve to check the flying ions or electrons. In the upper end of the supporting tube (Fig. 1) is secured besides the anode 33 a metal shield 49 surrounding the anode. The edges of this shield are also rounded off in the same manner as those of the intermediate electrodes and grids. The central portion of the shield is provided with an extension 41 engaging in a groove of the anode. In this manner rapidly flying ions or electrons are prevented from flying in the outward direction and from charging the supporting tube or the wall of the vessel. The supporting tube is held in position at the upper end thereof by means of the ring-shaped cap 42 held in position by a groove 43 arranged in the supporting tube with the aid of the ring 44. The cap ends in a tubular portion 45 which surrounds the upper squash of the discharge vessel. In this manner the radial position of the supporting tube as well as of the intermediate electrodes is determined. The axial position is determined with the aid of the resilient (slotted) ring 46 which on the one hand is secured in the tube 45 and on the other hand is insulatedly arranged with respect to the anode current supply rod 47. The resilient rings 46 can take up tensile or compressive forces but they are elastic transversely to the axis of the current bushing and prevent in this manner relatively great lateral forces from being transmitted to the current bushing. A device of a similar or of the same type for preventing axial displacements may also be provided for the cathode bushings. The two insulating rings 48 serve to insulate. The insulation is necessary at this point if the screen 49 is not to be directly connected with the anode. It is advisable to insert a resistance between the anode and this screen in order to prevent the screen from conducting current. The current supply to this screen is denoted by the numeral 50. The supporting tube is held in position at the lower end thereof by the U-shaped ring 51 which is integral with a cylindrical sleeve 52 and secured to the lower tubular portion of the control grid 31. The sleeve 52 surrounds the lower squash and prevents the lower end of the supporting tube from being displaced in the radial direction.

To prevent discharges along the inside wall of the discharge vessel it is preferable to arrange in the neighborhood of the current bushings for the intermediate electrodes, circular metallic coatings which are electrically connected to the current supplies and to the intermediate electrodes respectively. These metallic coatings may be made so thin that their electric resistance is so high that they are not appreciably heated when the discharge vessel is operated with high frequency. By the use of thicker rings the current path may be interrupted by slots, thus preventing

- an undesirable heating of these rings. These metallic coatings are denoted by the numeral 53. Externally of the discharge vessel they may be surrounded with protective caps (not shown) which may be provided with rounded off edges to prevent too high field densities (corona). 54 denotes an electrostatic screen surrounding the anode arrangement and which may be connected to the anode.
- 10 The type of the discharge vessel according to the invention permits to de-gas by high frequency all electrodes lying in the immediate neighborhood of the discharge and which are therefore heated in operation to a high temperature. So far as 15 an immediate transfer of heat between the electrodes and the wall of the vessel is possible, for instance, in the neighborhood of the cathode the metallic parts are given such a length that the parts lying in the neighborhood of the seal are not 20 appreciably heated in operation and therefore a de-gassing at a high temperature is not necessary.
- To prevent the ions or electrons from impinging upon the wall of the vessel and from causing 25 there disturbing discharges, the following provisions are preferably made:
- The anode is covered with respect to the vessel wall by a conductive screen which has substantially the anode potential. This screen may be connected to the anode, for instance, through a high 30 ohmic resistance of the order of magnitude of 10^4 ohm. In the gap between the anode and the above-mentioned screen engages a portion of the preceding intermediate electrode.
- 35 Fig. 8 is another embodiment of the invention, in which is shown only the upper part of the anode arm containing the anode. The anode arm may consist of glass but it may also be composed of a plurality of tube sections 61 of ceramic material, for instance, in the manner that the metallized 40 ends of the tubes are soldered to one another. 62' and 63 denote the series electrodes which are held in position by metallic rings lying between the single tube sections 61. A voltage lying between 45 the anode and cathode potential may be impressed on these tube sections, for instance, with the aid of a capacitive potentiometer. In this manner it is possible to render uniform the voltage distribution along the anode arm.
- 50 The intermediate electrodes consist of a plurality of concentrically arranged tubes having different diameters denoted by the numerals 64, 65, 66 and 67 secured to each other by means of studs. The tube 67 is flared at the upper end and encloses the next following electrode. By stepping 55 down the single tubes 64 to 67 in the vertical direction a field is attained between the intermediate electrodes which is characterized by the lines of force inclined to the axis of the tube. By such lines of force the ions or electrons are rapidly removed from the discharge path as long 60 as the discharge is not yet ignited. The anode 68 is supported by the current supply bolt 69. 70 is a metallic plate which closes the anode arm. The underside of the plate carries the calotte-shaped part 71 consisting, for instance, of graphite facing the concave portion of the anode. This construction permits in a known manner to adjust the anode without there occurring any 65 changes in the distance between the anode and the part 71. The cylindrical screen 72 surrounding the anode is secured to the part 71. The plate 70 is conductively connected to the part 71 and the screen 72 and is insulated from the anode by 70 the insulating body 73. Both parts may be con-
- nected to each other by means of the resistance 74. Under circumstances the insulating body 73 5 may be given a certain conductivity so that a particular resistor may be dispensed with. In the space between the anode 68 and the screen 72 extends the cylindric part 75 of the series electrode 73. Ions or electrons which impinge upon the anode can therefore only impinge upon the wall of the vessel after repeated reflection. It is hardly possible that the ions or electrons pass 10 in the space outside the screen 72 so that no detrimental discharges can be produced by the small quantity of ions or electrons entering this space. 76 is a spherical screen which prevents the corona phenomena on the outer parts of the anode construction.
- What is claimed is:
1. A gas- or vapor-filled discharge vessel comprising an electron emitting source, an anode and intermediate electrodes arranged between said anode and the electron emitting source, the intermediate electrodes being secured in a tube of quartz or ceramic material carrying the same and which is arranged in the discharge vessel. 20
  2. A gas- or vapor-filled discharge vessel comprising an electron emitting source, an anode and intermediate electrodes arranged between said anode and the electron emitting source, the intermediate electrodes being secured in a tube of quartz or ceramic material carrying the same and 30 which is arranged in the discharge vessel, the intermediate electrodes being supported by springs with respect to the supporting tube. 25
  3. A gas- or vapor filled discharge vessel comprising an electron emitting source, an anode and intermediate electrodes arranged between said anode and the electron emitting source, the intermediate electrodes being secured in a tube of quartz or ceramic material carrying the same and which is arranged in the discharge vessel, the 35 leads to the anode or cathode being connected to the supporting tube through resilient members so as to prevent lateral forces from being transmitted to the anode current supply leads. 40
  4. A gas- or vapor filled discharge vessel comprising an electron emitting source, an anode and intermediate electrodes arranged between said anode and the electron emitting source, the intermediate electrodes being secured in a tube of quartz or ceramic material carrying the same and which is arranged in the discharge vessel, the 45 intermediate electrodes being surrounded by U-shaped rings which close the space between the electrodes and the supporting tube. 50
  5. A gas- or vapor-filled discharge vessel comprising an electron emitting source, an anode and intermediate electrodes arranged between said anode and the electron emitting source, the anode being covered with respect to the discharge vessel wall by a conductive screen and a part of the intermediate electrode extending into the gap between the screen and the anode, said screen being secured to a metal cover plate of the anode arm and the anode supply lead being connected to said plate. 55
  6. In an electrical discharge vessel, an anode, a cathode, and a plurality of intermediate electrodes collectively forming walls about the discharge path therebetween, the ends adjacent the cathode of individual intermediate electrodes telescoping into and extending within the adjacent intermediate electrode. 70
  7. In an electrical discharge vessel, an anode, a cathode, and a plurality of intermediate electrodes collectively forming walls about the dis- 75

charge path therebetween, the ends of individual intermediate electrodes telescoping into and extending within the adjacent intermediate electrode and having their cross-sections subdivided 5 by longitudinally extending partitions.

8. In an electrical discharge vessel, an anode, a cathode, and a plurality of intermediate electrodes collectively forming walls about the discharge path therebetween, the ends of individual 10 intermediate electrodes telescoping into and extending within the adjacent intermediate electrode and having their cross-sections subdivided

by longitudinally extending partitions, and means for impressing voltages intermediate between those of said anode and cathode on said intermediate electrodes, the potential difference between the anode and the adjacent intermediate electrode 5 being less than that between adjacent intermediate electrodes, whereby the voltage distribution during switching operations is more evenly distributed thereby protecting the ends of the discharge vessel from excessive voltage strains. 10

MAX STEENBECK.
